CLOCK OR SIMILAR ARTICLE

William V. Judson, Westport, Conn., assignor to General
Electric Company, a corporation of New York

Filed Jan. 27, 1967, Ser. No. 5,590

Term of patent 7 years

(Cl. D42—7)

Fig. 1.

Fig. 2.

Fig. 3.

Fig. 4.

Fig. 5.

FIG. 1 is a front perspective view of a clock embodying my new design;

FIG. 2 is a front elevational view thereof;

FIG. 3 is a side elevational view thereof;

FIG. 4 is a rear elevational view thereof; and

FIG. 5 is a top plan view thereof.

The essential features of the design are shown in full lines. The ornamentation partially shown in FIG. 1 is understood to continue over the complete surface of the face as shown in FIG. 2.

I claim:

The ornamental design for a clock or similar article, substantially as shown and described.
